UNITED STATES PATENT OFFICE.

ELLSWORTH A. HAWTHORNE, OF BRIDGEPORT, CONNECTICUT.

ACOUSTIC APPARATUS.

1,158,049.

Specification of Letters Patent.

Patented Oct. 26, 1915.

Application filed February 5, 1913. Serial No. 746,260.

To all whom it may concern:

Be it known that I, ELLSWORTH A. HAWTHORNE, a citizen of the United States, and a resident of Bridgeport, county of Fairfield, and State of Connecticut, have invented an Improvement in Acoustic Apparatus, of which the following description, in connection with the accompanying drawings, is a specification, like characters on the drawings representing like parts.

This invention relates to acoustic apparatus, and more especially to mechanically driven horns of that general type in which a rapidly driven body is caused to vibrate the sounding means to produce a warning signal, the apparatus being particularly useful for motor vehicles.

My invention will be best understood by reference to the following specification, when taken in connection with the accompanying drawings of one specific embodiment thereof, while its scope will be more particularly pointed out in the appended claims.

In the drawings: Figure 1 is an elevation, partly in section, of one form of acoustic apparatus embodying my invention, as applied to a motor vehicle, a portion of the latter being shown conventionally; Fig. 2 is a central longitudinal section, partly in elevation, of the sound amplifier and the sound-producing devices therein; and Fig. 3 is a sectional view on line 3-3 of Fig. 2, looking toward the right.

Referring to the drawings, and to the embodiment of my invention which I have there shown for illustrative purposes, 4 is a suitable casing forming a sound chamber 5, said casing herein being in the form of a sound amplifier having a sound-delivering opening 6. Within the sound chamber 5, there is provided a plurality of sets of sounding elements and striking elements. In the present instance, the sounding elements are in the form of vibratory elastic reeds, or the like, 7, and the striking elements are in the form of pins 8. While the striking elements and sounding elements may be otherwise suitably arranged, herein the sounding elements are secured to a diaphragm 9, suitably supported in the amplifier, and the striking elements 8 are secured to a suitable rotatable body 10, herein in the form of a disk secured to a shaft 11, the latter being axially disposed within the amplifier. The shaft 11 may be journaled in

suitable bearings 12 and 13, the latter being herein supported by a spider 14.

In the embodiment of my invention selected for illustration, the sounding elements and striking elements are arranged in several sets, each set including a plurality of striking elements, herein two, and a plurality of sounding elements, herein two, (see Figs. 2 and 3). If desired, the sounding elements of each set may have a different sound characteristic as compared with the other sets, and if desired, such difference may be provided for by making the elements of each set a different length from the elements of the other sets. In such case, of course, the striking elements 8 will be suitably proportioned to coöperate with their respective sounding elements. The latter in practice will consist of suitable vibratory bodies, as for example thin elastic metal herein secured to the diaphragm 9 in any suitable manner, as by securing strips 15.

While the striking elements 8 may be otherwise suitably arranged, they are herein disposed on two spiral lines, as it were (see Fig. 3), so as to strike the sounding elements successively. Any suitable means may be provided relatively to rotate the shaft 11, and amplifier 4, to cause the striking elements successively to engage their coöperating sounding elements in rapid succession, thereby to sound the sounding elements. Herein the amplifier 4 is fixed, while the shaft 11 is rotated at high speed, although this arrangement might obviously be reversed. The shaft 11 is herein driven from a power shaft 16 of a motor vehicle, the latter being designated generally by the numeral 17. While any other suitable means may be provided for utilizing the rotative movement of the power shaft at will to drive the shaft 11, the latter is herein provided with a suitable pulley 18, connected by a belt 19 to a pulley 20 on the shaft 16, and the latter is provided with a suitable friction clutch comprising two clutch members 21 and 22. The latter may be shifted into and out of engagement with its coöperating member by suitable means, as for example a clutch shifting lever 23 of common form, operated by a foot button 24, there being provided a suitable spring 25, normally to retain the clutch members disengaged. By simply pressing the foot button 24, the clutch may be engaged, thereby causing the

shaft 11 to be driven at high speed, thus causing the successive engagement of the several sets of striking elements 8 with their coöperating sounding elements 7. The character of the sound produced may, of course, be varied by suitably varying the shape or length of the sounding elements or the material of which they are composed. The character of the sound produced will, of course, 10 vary in pitch and quality, according to the character of the sounding devices which may, of course, be altered within the spirit and scope of my invention. The sound waves produced will pass out through the 15 annular space around the disk 10, and through the mouth of the amplifier into the air.

While I have herein shown and described one form of my invention for illustrative 20 purposes, and have disclosed and discussed in detail the construction and arrangement incidental to one specific application thereof, it is to be understood that the invention is limited neither to the mere details or 25 relative arrangement of parts nor to its specific embodiment herein shown, but that extensive deviations from the illustrative form or embodiment of the invention may be made without departing from the principles 30 thereof.

Having thus described my invention, what I claim and desire by Letters Patent to procure is:—

1. An acoustic apparatus comprising an 35 elastic vibratory diaphragm, a plurality of sounding elements secured to said diaphragm, means for sounding said elements in succession to cause said diaphragm to vibrate, and means for directing the sound 40 so produced in a direction transverse to the plane of said diaphragm.

2. An acoustic apparatus comprising a vibratory diaphragm, a plurality of sounding elements secured to said diaphragm, 45 means for sounding said elements in succession to cause said diaphragm to vibrate, and means for amplifying and directing the sound so produced in a direction transverse to the plane of said diaphragm.

50 3. An acoustic apparatus comprising a sound chamber having an opening, a shaft disposed within said chamber and extending toward said opening, a plurality of sounding elements extending lengthwise of

said shaft within said chamber, and means 55 carried by said shaft for sounding said elements in succession.

4. An acoustic apparatus comprising a sound chamber having an opening, a shaft disposed within said chamber and extending 60 toward said opening, a plurality of sounding elements extending lengthwise of said shaft within said chamber, a disk carried by said shaft, and means carried by said disk for sounding said elements in succession. 65

5. An acoustic apparatus comprising a sound chamber having an opening, a shaft disposed within said chamber and extending toward said opening, a plurality of sounding elements having different sound characteristics disposed longitudinally of said shaft within said chamber and extending toward said opening, a rotary body disposed within said chamber, and a plurality of striking members carried by said body lengthwise of 70 said shaft and arranged for coöperation with said sounding members.

6. An acoustic apparatus comprising a sound chamber, a vibratory diaphragm, a plurality of sounding elements secured to 80 said diaphragm, and a rotary body carrying striking means coöperating successively with said sounding elements to cause said diaphragm to vibrate.

7. An acoustic apparatus comprising an 85 amplifier, a relatively thin vibratory diaphragm within said amplifier, a plurality of sounding elements secured to said diaphragm within said amplifier, and means for causing said sounding elements to be 90 sounded successively and cause said diaphragm to vibrate.

8. An acoustic apparatus comprising an amplifier, a relatively thin vibratory diaphragm within said amplifier, a plurality of 95 sounding elements secured to said diaphragm within said amplifier, and means within said amplifier for causing said sounding elements to be sounded successively and cause said diaphragm to vibrate. 100

In testimony whereof, I have signed my name to this specification, in the presence of two subscribing witnesses.

ELLSWORTH A. HAWTHORNE.
